UNITED STATES PATENT OFFICE.

ALBERT H. DE VOE, OF CHICAGO, ILLINOIS.

HEMMING AND CORDING ATTACHMENT FOR SEWING-MACHINES.

SPECIFICATION forming part of Letters Patent No. 696,417, dated April 1, 1902.
Application filed July 11, 1900. Serial No. 23,209. (No model.)

To all whom it may concern:

Be it known that I, ALBERT H. DE VOE, a citizen of the United States of America, residing at Chicago, in the county of Cook and 5 State of Illinois, have invented certain new and useful Improvements in Attachments for Sewing-Machines, of which the following is a specification.

My invention relates to certain improvements in attachments for sewing-machines, the object of which is to so combine a hemming attachment and a cording attachment as to enable the same to be used conveniently in connection with the same seam.

15 In the sewing on of a flounce, either plain or ruffled, in ordinary dressmaking it is usually necessary to sew a number of seams, because it is desirable to sew a bound cord into the seam and turn the latter so as to throw 20 the flounce out from the other goods. Furthermore, it has been exceedingly difficult, if indeed it has been heretofore possible, to sew on a ruffle of the sort herein shown except at the edge of a piece of goods. It is my 25 purpose to provide means whereby the cord may be bound and sewed in and the flounce or ruffle sewed on by a single seam and without preliminary preparation of the hem or other portions thereof.

30 To such end the invention consists in certain features of novelty below described and claimed.

In the drawings, Figure 1 is a plan of the complete attachment embodying in their preferred form the essential features of my invention. Fig. 2 is an elevation from the front; Fig. 3, a vertical section in line 3 3 of Fig. 1; Fig. 4, a horizontal section in line 4 4 of Fig. 8 of a cording device alone. Fig. 5 is a plan 35 of the working portion of the device with the cloth therein. Fig. 6 is a vertical section in line 6 6 of Fig. 5. Fig. 7 is a similar section in line 7 7 of the same figure. Fig. 8 is a similar section in line 8 8 of the same figure. Fig. 45 9 is also a similar section in line 9 9 of said figure, and Fig. 10 is a perspective view showing a flounce or ruffle and bound cord secured upon a piece of cloth.

50 Referring to the figures, A is a bracket adapted to be screwed to the bed of a sewing-machine by means of holes to be provided in the latter at the proper places. This bracket extends

upward from the bed and has a laterally-projecting arm a, from the outer end of which extends downward a post a', upon the bottom of which is pivoted a swinging arm b by means of a bolt a³, a stud b' on the arm and a clamp C upon the post, provided with a shoulder c, forming an adjustable stop for the swinging arm to limit its motion in one direction— 60 namely, that in which it is pulled by the cloth passing through the attachment. The arm b is formed in two parts b² b³, secured together by clamping-screws b⁴ b⁵, threaded in one of the parts and working in a slot in the other. This 65 gives a longitudinal adjustment to the arm, making up, together with the angular adjustment afforded by the clamp C, a universal adjustment for the attachment carried by the end of the arm. Said attachment, as here 70 shown, has an ordinary hemmer D, and because of the pivotal connection of the arm with the post the same may be swung toward the operator and away from the needle when desirable for any purpose and may be returned 75 to the proper position for work by swinging it toward the needle as far as the stop will permit. The bracket A has secured to it a rod E, extending past the hemmer and having beyond the same a longitudinally-adjustable sleeve F, provided with a laterally-extending arm f, terminating in a downwardly-extending piece f'. To the bottom of this post is pivoted a horizontally-swinging arm G by means of a bolt f², and an angularly- 80 adjustable clamp H, provided with a shoulder h, secured to the post, and a stud g on the arm form an angularly-adjustable stop to limit the swing of said arm. Upon the end of the arm is secured a cord and binding- 85 guide J, the end of which is provided with a slot j for the binding and an eye j^a for the cord, the guide being shaped to fold the binding down upon the cord and the device being so located when swung into the hemmer 90 as to guide the cord and binding beneath the hem, so as to be sewed down by the latter. The free end of the arm G has a forwardly-projecting finger extending therefrom, preferably serrated upon its end and adapted to 95 assist in guiding the cloth to the needle.

The entire attachment is secured to the machine-bed by screws a⁴ and need not be disturbed for any adjustment of the operat-

ing parts. The latter may be adjusted longitudinally of the attachment to bring the seam wherever desired on the hem. Either or both of them may be swung back toward the operator for any purpose, and the cord- 5 ing device may be thus swung to enable the binding and cord to be inserted.

The attachment may be used in connection with a ruffler or not, as may be desired.

10 In Figs. 6, 7, and 9 the cloth is shown, and the finished seam in Fig. 10.

K is the cloth itself, which is here shown as doubled back, so as to sew a ruffle along an intermediate portion thereof. The ruffle is 15 shown at M, the cord at N, the binding at O. k is the under thickness of the cloth as it goes through the hemmer; k', the upper. Fig. 10 represents the way the ruffle hangs on a skirt, k' being the upper portion of the cloth 20 and k the lower portion. In the seam here shown the stitching is sufficiently far from the edge of the hem on the side of the ruffle to allow the hem to bend down under the weight of the ruffle and throw the latter out 25 farther from the cloth than otherwise. Furthermore, by the use of the hemmer arranged in the manner shown and described the cord, binding, and ruffle may be sewed along an intermediate portion of the cloth by one operation and in such a manner that no stitches 30 are visible on the finished work, Fig. 10.

All of the features of novelty are not necessarily essential to my invention broadly considered, as certain features thereof may 35 be used independently of the others, and I therefore do not limit myself to the specific construction or arrangement except as definitely pointed out in the claims.

I claim as new and desire to secure by Letters Patent—

40 1. In a sewing-machine attachment, the combination with a suitable supporting-frame, of a hemmer carried by an arm pivot-

ed to said frame to swing horizontally thereon and provided with a stop to limit said horizontal movement, a coöperating attachment adapted to direct material into the hem, and an arm carrying said coöperating attachment, also pivoted to said frame to swing horizontally toward and away from the hemmer and 45 a stop to limit the horizontal movement of said latter arm; substantially as described. 50

2. In a sewing-machine attachment, the combination with a suitable supporting-frame, of an arm longitudinally adjustable 55 with respect thereto and pivoted to swing horizontally thereon, a hemmer supported on the end of said arm, a second arm also longitudinally adjustable with respect to said frame and pivoted to swing horizontally 60 thereon, stops for limiting the horizontal oscillation of said arms and a suitable attachment upon the end of the second arm adapted to direct material into the hemmer; substantially as described. 65

3. In a sewing-machine attachment, the combination with a suitable frame, of a hemmer carried by an arm pivoted to said frame to swing horizontally thereon, an adjustable stop to limit said horizontal movement, a coöperating attachment adapted to direct material into the hem, an arm carrying said coöperating attachment also pivoted to the frame to swing horizontally toward and away 70 from the hemmer and an adjustable stop to limit the horizontal movement of said latter arm; substantially as described. 75

In witness whereof I have hereunto set my hand, at Chicago, in the county of Cook and State of Illinois, this 9th day of July, A. D. 80 1900.

ALBERT H. DE VOE.
